PUMP

Ernest Arthur Franks, Whitchurch, Wales

Original application January 11, 1935, Serial No. 1,400. Divided and this application September 9, 1935, Serial No. 39,851. In Great Britain October 30, 1934

12 Claims. (Cl. 123—139)

This application is a division of my application No. 1,400, filed January 11th, 1935.

This invention relates to pumps and more especially to pumps for supplying fuel to Diesel and 5 other compression ignition engines.

The invention is particularly concerned with an arrangement which comprises two pistons discharging to a common discharge and operable through followers by rotary cams at least one of 10 the followers being movable to advance or retard the follower with respect to its cam so as to vary the phase relationship of the two pistons.

The main object of the present invention is to 15 provide improved means whereby the fuel supplied by the two pistons can be regulated.

According to the present invention in a fuel pump which comprises two pistons discharging to a common discharge and operable through followers by rotary cams, a movable regulating member being provided for at least one of the 20 followers to advance or retard the follower with respect to its cam and so to vary the phase relationship of the two pistons. The or each movable follower is so slidably mounted in the regulating member as to be constrained to move in the same direction as that of its associated piston while the regulating member is constrained to move in a plane which is transverse with respect 25 to the said direction of movement of the piston.

In Diesel or compression ignition engines, it 30 is necessary that the delivery be under control and capable of quick and definite regulation as between maximum and "no" delivery, it being further necessary that the point of commencement of delivery in relation to the engine cycle be under control so as to get the best firing point for different loads on the engine.

To effect this there is provided a pump element 35 having two pistons (or a piston and slide valve) driven by mechanism which is adapted to reciprocate the pistons in an adjustable out-of-phase relationship. These two pistons open into a common delivery chamber so that while the pistons are operating in the same sense, both operate to deliver fuel, but when one piston operates in the reverse sense, the delivery of one is taken by the other so that no effective delivery is established: by alteration of the two phases simultaneously the timing of effective delivery is 40 adjusted and by altering the phases relatively to one another, the effective delivery is adjusted.

Where the total volume required to be delivered by the pump would be extremely small when divided between two pistons, one of the pistons 45 which may be larger than the other could act as

the delivery pump and the other as a piston or spill valve. The construction of both pistons would be the same excepting that as the piston forming the piston valve was made smaller in area the stroke would be increased to give the 5 same volume as the delivery pump or the profile of a cam for operating this piston be so formed as to release the piston forming the spill valve at the required moment for the cessation of delivery of the fuel.

In any case it is desirable that the piston acting as the piston or spill valve should have a clearance volume somewhat in excess of the delivery piston proper so as to cause a partial vacuum in the chamber common to the two pistons 10 at the instant of cut off. This can be effected either by a difference in pump diameter or in the stroke as allowed by the cam profile.

The invention is illustrated in the accompanying drawings as applied to a pump incorporating 15 the invention described and claimed in the pending application Serial No. 1,400, filed January 11, 1935.

In the drawings, Figure 1 is a longitudinal section partly in elevation, Figure 2 a section on the line II—II Figure 1, Figure 3 a section on the line III—III Figure 1, Figure 4 a detail plan view, Figure 5 a section on the line V—V Figure 1, Figure 6 a detail elevation and Figures 7 and 8 views similar to Figure 4 of a modification.

The arrangement illustrated in the accompanying drawings is a multi-unit pump arrangement (i. e. an arrangement comprising a plurality of pump units) and while for convenience reference has been made to the parts of one unit, in the drawings corresponding parts of the various units have been given corresponding numerals.

In the drawings each pump element consists of two diameter rods 1, 3 and 1', 3' working in two diameter cylinders 2, 2', 5, 5', the smaller diameter parts of the cylinders 2 and 2' opening into a common chamber 4 having a spring loaded outlet valve 12. The valve 12 is carried by a plug 12' having a tapered lower face co-operating with a tapered washer 12² to provide an air-tight joint. The rods are formed of two diameters for the purpose described in the specification of the application Serial No. 1,400, but for the purposes of the present invention it is merely necessary to 40 discuss the smaller diameter parts 1 and 1' of the rods and to regard them as two pump elements discharging into a common chamber 4. The parts 2, 2' of the cylinders in which the pistons 45 1 and 1' operate communicate through a 50 55

valve 13 and a passage 11 with a chamber 10, the various chambers being interconnected by a passage 16 and these chambers are supplied with fuel in the arrangement shown by the larger diameter parts 3, 3' of the rods 1, 1' which feed fuel from a passage 7 and passage 6 to the chambers 10 through passages 8 and past non-return valves 9.

The pumping effect is obtained by reciprocating the rods forming the pistons 1, 3 and 1', 3' by a cam 26 through intermediate members or followers 27, 27'.

The intermediate members or followers 27, 27' are of square cross section and are mounted to reciprocate in the same direction as the pistons 1 and 1' in apertures formed between the two opposed end walls of square apertures formed in sliding plates or regulating members 28, 28' and two opposed side or filling pieces 28², 28³ which are interposed between the members 27, 27' and the side walls of the apertures in the plates 28, 28' lying tangentially with respect to the shaft 29 on which the cam 26 is mounted and at right angles with the axis of the pump rod. The plates 28, 28' are movable in a direction which is in a plane transverse with respect to the direction of movement of the pistons.

The two rods forming the piston 1, and 1' are spring loaded so as to hold them against their intermediate members 27, 27' and these members against their cam 26, this preferably being effected by a single spring 30 which is coiled around a stationary pin 31 and has its central portion 32 extended to form a reaction point and its two ends 33 received within apertures in the respective rods.

The movement of the sliding plates 28, 28' is regulated by a tongue or protuberance 34, 34' extending across the sliding plate at an inclination to the axis of the cam shaft, the tongues engaging grooves formed in a plane parallel with the plane of movement of the plates 28, 28' but in a transverse direction with respect to the direction of movement of the plates 28, 28'.

With the construction described it will be seen that by moving the sliding plates 28, 28' the intermediate members 27, 27' are moved to be advanced or retarded with respect to the cams and that this movement of the plates is effected by moving the control bars 35, 35'.

Any movement will, of course, cause an earlier or later movement (with respect to the cam) in a reciprocating motion of the piston associated with the cam.

The degree of sensitiveness of adjustment is a measure of the angle of the grooves or tongues. The smaller the angle formed between a line passing through the centre of the tongue and a line representing the direction of movement of the bars, the greater will be the length of travel of the associated bar 35 or 35' to effect a similar movement of the sliding plates 28, 28'. And, further, the smaller the angle as mentioned the less will be the reaction of the cam thrust on the sliding plates and with a very small angle and a long travel of the control bars 35, 35' the reaction is very small and the control takes place in a plane approaching right angles to the plane of reaction of the sliding plates.

Any thrust imparted to the control bars in a horizontal direction may be taken up either by the walls of the casing of the apparatus, or where necessary by rollers or ball bearings 37, and the bar sliding in a direction at right angles to such thrust, is free from any reaction. The sliding

plates may also be provided with balls or rollers 38 to permit easy sliding thereof.

Three regulations are possible with this mechanism:

(1) Both control bars 35, 35' are free to move but the control bars are connected by a gear wheel 39 or by links in such a manner as to select a moment for commencement of delivery dependable upon the quantity of fuel to be delivered, thus automatically ensuring the fuel injection meeting the load placed upon the engine. An arrangement employing a gear wheel 39 is shown in Figure 4 and the angles of the grooves in the two control bars bear such a ratio that a movement imparted to one control bar 35 although transmitted equally to the other control bar 35' causes a smaller movement of one sliding plate 28 than of the other 28', and hence the change in position of one intermediate member 27 with respect to the cam 26 is less than the change of the other intermediate member 27' with respect to the cam 26. Thus, suppose the period of delivery of the piston 1' is to extend over say 15° and it is desired to have control of 6° advance in injection, then the control bar 35' for the piston 1' will have to control over 21° whilst the control bar 35 for the piston 1 will control over only 6°. The ratio of the angle of the slots in the control bars 35, 35' would thus be 6:21.

Alternatively the arrangement shown in Figure 7 could be employed to give a similar result, the desired ratio in the movements of the plates 28, 28' being obtained by having a link 40 by which a movement of the control bar 35' is transmitted to the plate 28' in the ratio of 21:6, the angles of the grooves in the plates being equal as is shown.

The regulation of delivery as described is effected by hand for quick operation but for regular running and the other conditions imposed on the fuel supply there is provided a governor.

The governor consists of a liquid supply, preferably lubricating oil of low viscosity, to a chamber in which reciprocates a piston or the like on one control bar, this bar having a reaction spring. There is also provided in the liquid supply a controlled orifice such as a needle valve or the like.

It is known that with a constant volume delivery pressure rises as the outlet is reduced and this variation in pressure is employed to cause reciprocation of the piston connected to the control bar.

A corollary of this is that with a fixed size orifice variations in quantity will cause variations in pressure and this also is made use of in causing the reciprocation of the control bars.

Liquid supply, which is effected at a ratio proportional to the speed of the engine, is obtained in the arrangement shown by two plungers 41, 42 which are positively reciprocated by cam grooves 43, 44 in discs secured to the shaft 29 the plungers 41, 42 having pins 45, 46 entering the cam grooves. These plungers when at one end of their stroke uncover passages 47 opening to a supply chamber 48 to allow liquid to flow into the plungers: this liquid is forced by the plungers 41, 42 when moving on their delivery stroke past non-return valves 49, 50 to a chamber 51 which is common to the plungers and this chamber is provided with the regulatable orifice indicated at 52 and with a connection 53 to the cylinder 54 in which reciprocates the piston 55 connected to the control bar 35. The orifice is regulated by a valve 56 which has a screw threaded shank 57 so that by rotating the shank, the orifice is covered or uncovered to 75

a greater or lesser extent, the orifice opening into the chamber 48.

It will now be seen that if the valve 56 be operated by closing or opening, the pressure applied by liquid to the piston will increase or decrease and the control bars will be caused to move, thus increasing or decreasing the quantity of fuel delivered to the engine.

If the valve be set, then increase or decrease 10 in the speed of the engine will cause greater or lesser pressure to be applied to the piston 55 and hence to the control bars and tending to cause steadyng of the engine running.

Such a governor can be made extremely sensitive 15 and quick in control by the correct proportions of the components.

(2) By fixing one control bar and allowing the other to be moved, a fixed moment for commencement of delivery and variable moment for 20 cessation of delivery would be obtained. This can be obtained by an arrangement as shown in Figures 4 and 7 but omitting the gear wheel 39 or the link 40, the movable control bar being operated by hand by being coupled to some 25 form of hand control, or worked by a governor such as that described. The object of providing the other (or normally fixed) control bar in this case is to provide for adjustment from time to time and to meet the various conditions of 30 different engines: or an arrangement as shown in Figure 8 can be employed in which case only one control bar 35 is employed, the other control bar being omitted and the sliding pieces 28' are secured by pegs 28⁴.

(3) Both control bars free to move independently. This would give a variable moment for commencement of delivery and a variable moment for cessation of delivery.

The double piston arrangement described also 40 possesses the further advantage of distributing the power required to operate the pump.

As has been stated the drawings incorporate apparatus in accordance with the invention described and claimed in the co-pending application Serial No. 1,400 and to effect this the pistons 1 and 1' are made a slack fit in their cylinders and the pistons 3, 3' feed fuel not only to the chambers 10 but also to the clearance left by the slack fit. In addition the 50 chamber 10 is in communication with the passage 16 extending through a chamber 16' and passage 16² and tube 20 to a vent formed by a spring loaded valve 17 which opens when the pressure of the fuel fed by the second piston 3 exceeds the spring loading: the opening of the valve places the passage 16 and hence the chamber 10 open to a low pressure vent passage 18 and the fuel displacement of the second piston 3 is arranged to be in excess of the 55 requirements per cycle. Thus excess fuel, together with air, is allowed to pass through the vent 17 which remains open until the second piston 3 ceases to displace fuel.

Furthermore, as is also described and claimed 60 in the said application, Serial No. 1,400, the tube 20 extends into a second tube 21 depending from a block 22 carrying the valve 17 the second tube 21 extending into a tubular casing 23 closed at its upper end by the block 22 the casing being closed at its lower end; the first tube 20 is spaced at its upper end from the block 22 and the lower end of the second tube 21 is spaced from the tubular casing; mercury or other liquid indicated at 24 and which will 65 prevent the passage of air or other gas, and will

not react with the fuel is contained in the annulus between the second tube 21 and the casing 23 and between the second tube 21 and the first tube 20 and it will be seen that air trapped above the mercury in the annulus between the 5 second tube 21 and the casing 23 will be compressed when fuel pressure conditions rise and the air will react to maintain this pressure on the fuel. The interposition of mercury or other liquid between the air and the fuel prevents 10 the air from passing to and mixing with the fuel. In order to prevent the spilling of mercury should the device become inverted, the first tube may have at its upper end a small orifice which, while allowing fuel to pass, will 15 prevent or offer a large resistance to the passage of mercury.

58 is a reservoir from which lubricating oil is supplied to a passage 15 for supplying oil to grooves 14, 14' in the pistons 3, 3'. This is effected by a further plunger 59 which is held by a spring 60 in engagement with a cam 61 on the shaft 29. This plunger during its suction stroke draws oil from the chamber 58 past a non-return valve 62 and during its delivery stroke 20 25 delivers the oil to the passage 15 past a non-return valve 63. In order to prevent the generation of unduly high pressure, a relief valve is in the form of a piston 64 which carries the valve 62 and is urged by a spring 66, this spring being such as to allow the piston to be displaced against the spring 66 when the pressure generated by the plunger exceeds a predetermined 30 value. 35

In order to prevent the pressure in the passage 15 from dropping an excessive amount when the plunger 59 moves on its suction stroke a plug 15' closing the end of the passage 15 is arranged to form a housing for a spring loaded 40 plunger 15² which reacts to maintain pressure in the passage 15. Alternatively a spring loaded diaphragm could be employed. Said plunger 15² provides resilience in the system so that the capacity of the system may vary, the plunger 45 being spring loaded for this purpose so as to give or yield when the capacity of the system is required to increase.

It is well known that the small pocket of air in a pumping system prevents a "snappy" cut-off 50 in the delivery and it is further well known that air lodged in the system will prevent the functioning of a pump.

To ensure any air in the pump system being expelled without the necessity for turning the engine supplied by the pump system a small hand operated piston pump 67 is provided in communication through a non-return valve 68 with the fuel supply passage 7 and through a non-return 55 valve 69 with the storage pressure side of the pumps (i. e. with the passage 16); this hand operated pump forces fuel through all the passages and drives air out through the spring loaded vent 17. 60

It is preferred to form the casing of the pump assembly in two parts which are held together by dove-tailed recessed plates 70, the dove-tailed sides being slightly tapered, which engage projections 71 which are formed conjointly by the 65 two parts and are similarly tapered: thus, by forcing the plates 70 on to the projections 71, the two parts are drawn firmly together.

It will be obvious that the invention is not limited in its application to a multiple pump nor 70

to a pump incorporating the invention according to the specification Serial No. 1,400.

What I claim is:—

1. In a fuel pump, two reciprocable pump elements, a conduit into which both elements discharge, rotary cam mechanism reciprocating the pump elements, followers interposed between the cam mechanism and pump elements, guide members in which the followers are slidably guided and constrained to move in the same direction as the respective pump elements, means mounting at least one of the guide members for movement in a plane transverse with respect to the direction of movement of the follower guided thereby, and means to effect movement of the movable guide member to vary the position of the associated follower with respect to the cam mechanism.
2. In a fuel pump, two reciprocable pump elements, a conduit into which both elements discharge, rotary cam mechanism reciprocating the pump elements, followers interposed between the cam mechanism and pump elements, guide members in which the followers are slidably guided and constrained to move in the same direction as the respective pump elements, anti-friction means mounting at least one of the guide members for movement in a plane transverse with respect to the direction of movement of the follower guided thereby, and means to effect movement of the movable guide member to vary the position of the associated follower with respect to the cam mechanism.
3. In a fuel pump, two reciprocable pump elements, a conduit into which both elements discharge, rotary cam mechanism reciprocating the pump elements, followers interposed between the cam mechanism and pump elements, guide members in which the followers are slidably guided and constrained to move in the same direction as the respective pump elements, means mounting at least one of the guide members for movement in a plane transverse with respect to the direction of movement of the follower guided thereby, a control member for the movable guide member, means mounting the control member for movement in a plane parallel with that of the guide member and in a direction at right angles to the direction of movement of the guide member, and an inclined tongue and groove connection between the control member and the guide member so that movement of the control member effects movement of the guide member to vary the position of the associated follower with respect to the cam mechanism.
4. In a fuel pump, two reciprocable pump elements, a conduit into which both elements discharge, rotary cam mechanism reciprocating the pump elements, followers interposed between the cam mechanism and pump elements, guide members in which the followers are slidably guided and constrained to move in the same direction as the respective pump elements, anti-friction means mounting at least one of the guide members for movement in a plane transverse with respect to the direction of movement of the follower guided thereby, a control member for the movable guide member, anti-friction means mounting the control member for movement in a plane parallel with that of the guide member and in a direction at right angles to the direction of movement of the guide member, and an inclined tongue and groove connection between the control member and the guide member so that movement
- of the control member effects movement of the guide member to vary the position of the associated follower with respect to the cam mechanism.
5. In a fuel pump, two reciprocable pump elements, a conduit into which both elements discharge, rotary cam mechanism reciprocating the pump elements, followers interposed between the cam mechanism and the pump elements, guide members in which the followers are guided to move in the same direction as the associated pump elements, means mounting the guide members for movement in a plane transverse with respect to the direction of movement of the followers guided thereby, and means effecting movement of the guide members in unison to vary the phase relationship between the two followers.
6. In a fuel pump, two reciprocable pump elements, a conduit into which both elements discharge, rotary cam mechanism reciprocating the pump elements, followers interposed between the cam mechanism and the pump elements, guide members in which the followers are guided to move in the same direction as the associated pump elements, means mounting the guide members for movement in a plane transverse with respect to the direction of movement of the followers guided thereby, control members one for each guide member, means guiding the control members for movement in a plane parallel with that of the associated guide member and in a direction at right angles to the direction of movement of the associated guide member, and inclined tongue and groove connections between control members and the guide members and means effecting simultaneous movement of the control members to vary the phase relationship between the two followers.
7. In a fuel pump, two reciprocable pump elements, a conduit into which both elements discharge, rotary cam mechanism reciprocating the pump elements, followers interposed between the cam mechanism and the pump elements, guide members in which the followers are guided to move in the same direction as the associated pump elements, anti-friction means mounting the guide members for movement in a plane transverse with respect to the direction of movement of the followers guided thereby, control members one for each guide member, anti-friction means guiding the control members for movement in a plane parallel with that of the associated guide member, and in a direction at right angles to the direction of movement of the associated guide member, and inclined tongue and groove connections between control members and the guide members and means effecting simultaneous movement of the control members to vary the phase relationship between the two followers.
8. Two pistons, two cylinders supported in parallel relationship and in which the two pistons are reciprocable, the cylinders opening into a common discharge, a rotary cam, followers interposed between the cam and the pistons, guide members in which the followers are constrained to reciprocate in the same direction as that of the pistons, means mounting the guide members for movement in a direction transverse with respect to the direction of movement of the pistons, control members disposed in opposite sides of the cylinders and movable in a plane parallel with the planes of the guide members and in a direction at right angles to the direction of movement of the guide members, means effecting movement of the control members, and means converting movement of the control members

into movement of the guide members to vary the setting of the followers relatively to the cam.

9. A plurality of pumps each comprising two pump elements discharging into a common discharge, rotary cam mechanism reciprocating the pump elements, followers interposed between the cam mechanism and the pump elements, guide members in which the followers are slidably guided and constrained to move in the same direction as the respective pump elements, means mounting at least one of the members for movement in a plane transverse with respect to the direction of movement of the follower guided thereby, a control member for corresponding movable guide members of all the pumps, means guiding the control member for movement in a plane parallel with that of the guide members and in a direction at right angles thereto, and means converting movement of the control member into movement at right angles thereto of the said movable guide members to vary the setting of the corresponding followers of the plurality of pumps with respect to the cam mechanism.

10. A plurality of pumps each comprising two pump elements discharging into a common discharge, rotary cam mechanism reciprocating the pump elements, followers interposed between the cam mechanism and the pump elements, guide members in which the followers are guided to move in the same direction as the associated pump elements, means mounting the guide members for movement in a plane transverse with respect to the direction of movement of the followers guided thereby, two control members one each for the corresponding guide members of the plurality of pumps, means guiding the control members for movement in a plane parallel with that of the guide members and in a direction at right angles to the direction of movement of the guide members, means converting movement of the control members into movement at right angles thereto of the guide members to vary the setting of the corresponding followers simultaneously, and means transmitting movement from one control member to the other control member.

11. A plurality of pumps each comprising two

pump elements discharging into a common discharge, rotary cam mechanism reciprocating the pump elements, followers interposed between the cam mechanism and the pump elements, guide members in which the followers are slidably guided and constrained to move in the same direction as the respective pump elements, means mounting at least one of the members for movement in a plane transverse with respect to the direction of movement of the follower guided thereby, a control member for corresponding movable guide members of all the pumps, means guiding the control member for movement in a plane parallel with that of the guide members and in a direction at right angles thereto, and inclined tongue and groove means converting movement of the control member into movement at right angles thereto of the said movable guide members to vary the setting of the corresponding followers of the plurality of pumps with respect to the cam mechanism.

12. A plurality of pumps each comprising two pump elements discharging into a common discharge, rotary cam mechanism reciprocating the pump elements, followers interposed between the cam mechanism and the pump elements, guide members in which the followers are guided to move in the same direction as the associated pump elements, means mounting the guide members for movement in a plane transverse with respect to the direction of movement of the followers guided thereby, two control members one each for the corresponding guide members of the plurality of pumps, means guiding the control members for movement in a plane parallel with that of the guide members and in a direction at right angles to the direction of movement of the guide members, inclined tongue and groove means converting movement of the control members into movement at right angles thereto of the guide members to vary the setting of the corresponding followers simultaneously, and means transmitting movement from one control member to the other control member.

ERNEST ARTHUR FRANKS.
